UNITED STATES PATENT OFFICE.

BENJAMIN F. KURTZ, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

LOCKING MECHANISM FOR DOOR-SUPPORTING MEANS.

Application filed February 6, 1924. Serial No. 690,937.

To all whom it may concern:

Be it known that I, BENJAMIN F. KURTZ, a citizen of the United States, residing in Bellevue, in the county of Allegheny and 5 State of Pennsylvania, have invented certain new and useful Improvements in Locking Mechanism for Door-Supporting Means, of which the following is a specification.

This invention relates to railway dump 10 cars and particularly to that type of car in which the discharge doors are supported or released by means of members which are movable into and out of supporting positions with the door and has for an object the 15 provision of means for locking said members in their door supporting positions.

Another object of the invention is to provide a connection between a plurality of door supporting and releasing members 20 whereby these members may be locked in their door supporting positions, and whereby free movement of the members is permitted when the door is being opened or closed.

25 These and other objects will be apparent from the following description.

Referring to the drawings in which like reference characters refer to like parts, Fig. 1 is a plan view of a portion of a railway 30 dump car embodying the invention. Fig. 2 is a side elevational view of the same, Figs. 3 and 4 are similar views of a modification of the invention and Figs. 5 and 6 are like views of another modification of the invention.

Referring now in detail to the drawings, the reference character 1 indicates the side wall of a railway car and 2 indicates a discharge door which is preferably hinged to, 40 or adjacent the center sill 3 and having its free edge adjacent the side wall 1. The door 2 is provided with members 4 which are secured to the door. These members preferably extend outwardly beyond the free edge 45 of the door and preferably beyond the side wall 1, and are adapted to be engaged by members 5 which are loosely mounted in brackets 6 secured to the side wall 1. Each of the members 5, adjacent its lower end is 50 provided with a ledge 7, the upper surface of which is adapted to engage with the outer end portion of one of the members 4, and when in such engagement will support the door in closed position. The pivot points

of the members 5 are so located that these 55 members will, after they have been moved out of engagement with the members 4, move by gravity to their door supporting positions. There are preferably two members 5 for each discharge door, which members are spaced apart and are operable in opposite directions.

To connect the members 5 together links 8 and 9 are provided, one end of the link 8 being loosely connected with one of the members 5 and one end of the link 9 being loosely connected with the other of the members 5, while the adjacent ends of these links overlap each other, and are preferably slidably connected together. On the link 8 a 70 dog or cam 10 is pivotally mounted, which is adapted to be moved into engagement with a portion of the link 9, to lock the members 5 in their door supporting positions, and movable out of such engagement 75 to permit the members 5 to be moved to their door releasing positions.

In Figs. 1 and 2 of the drawings the link 8 at one end is pivotally connected with one of the members 5 and at its opposite end is 80 provided with an outwardly extending flange 11, which has an opening 12 provided therein for the reception of the link 9. The link 9 at one end is pivotally connected with the other of the members 5 and at its opposite end is provided with an inwardly extending flange 13 which has an opening 14 85 provided therein for the reception of the link 8. The openings 12 and 14 are made slightly larger than the links 8 and 9 are in cross section, so 90 that free longitudinal movement between these links relative to each other is permitted, thus insuring the free movement of the members 5. When the members 5 are in their door supporting positions, the dog 10 95 is rotated and the cam surface thereof is brought into engagement with the outer surface of the flange 13, thus locking the members in their door supporting positions as clearly shown in full lines in Figs. 1 and 2. 100 When the dog or cam 10 is moved out of engagement with the link 9, and the members 5 are moved to their door releasing positions, the links will slide on each other, and move upwardly as shown in dot and dash lines in 105 Fig. 2 of the drawings. After the door has been released, the members 5 and links 8 and 9 will automatically move to their posi-

tions as shown in full lines in Fig. 2, and as the door is raised, the members 5 will be permitted to operate freely to their door supporting positions.

5 In Figs. 3 and 4 a modification of the invention has been illustrated, in which the link 9 is provided with an outwardly projecting flange 15, with which the dog or cam 10, pivotally mounted on the link 8, is adapted to engage to lock the members 5 in their door supporting positions. The link 8 is provided with a member 16 which projects outwardly and through a slot 17 formed in the link 9, while the link 9 is provided with 10 a like member which projects inwardly and through a slot 18, formed in the link 8. To prevent accidental separation of the links 8 and 9 each of the members 16 are provided with a nut 19, and washer 20, which washer 15 is of greater dimensions than the width of the slots. The connection between these links 8 and 9 will permit free longitudinal movement of one link relative to the other, in the same manner as described in connection with the construction as illustrated in Figs. 1 and 2.

In Figs. 5 and 6 a further modification of the invention has been illustrated, in which the link 9 intermediate its ends is provided 20 with an offset 21, with which the dog 10 or cam pivotally mounted on the link 8 is adapted to engage to lock the members 5 in their door supporting positions. The dog or cam 10 is pivotally mounted on a bolt 22, 25 which passes through the link 8 and through a slot 23 in one of the end portions of the link 9, such bolt being held against accidental movement by a nut 24, and washer 25. The end portion 26 of the link 8 is reduced 30 in width and passes through an opening in the offset portion 21 of the link 9, such opening being slightly larger than the end portion 26. The links 8 and 9, due to their loose connection will be free to move longitudinally, relative to each other in the same 35 manner as described in connection with the construction illustrated in Figs. 1 and 2 of the drawings.

In Figs. 3, 4, 5 and 6 the operation of the 40 members 5, when it is desired to open the doors or when it is desired to close them, is the same as described in connection with the device illustrated in Figs. 1 and 2.

It will be apparent to those skilled in the 45 art to which this invention appertains, that many minor changes may be made in the arrangement and details of the several parts of this device, without departing from the spirit and scope of the invention.

60 Having thus described the invention, what I claim as new and desire to secure by Letters Patent is:—

65 1. In a dump car, a discharge door, members movable into and out of supporting positions with said door, links connected with

said members and movable therewith said links being movable in the direction of their lengths, relative to each other, and means for locking said links against movement.

2. In a dump car, a discharge door, members movable into and out of supporting positions with said door, links connected with said members and movable relative to each other in the direction of their lengths, and means on one of said links adapted to engage the other of said links, to lock said members in their door supporting positions.

70 3. In a dump car, a discharge door, members movable into and out of supporting positions with said door, and means for locking said members in their door supporting positions, said means comprising inter-engaging members movable in the direction of their lengths relative to each other, and a locking member mounted on one of said members adapted to engage the other of said members.

75 4. In a dump car, a discharge door, members movable into and out of supporting positions with said door, and means for locking said members in their door supporting positions, said means comprising links connected with and extending between said members and movable in the direction of their length relative to each other, and a locking member mounted on one of said links adapted to engage the other of said links.

80 5. In a dump car, a discharge door, members movable into and out of supporting positions with said door, a plurality of links connected with said members and extending horizontally therebetween, a loose connection between said links whereby said links may move in the direction of their lengths 85 relative to each other, and means carried by one of said links adapted to engage the other of said links to lock said members in their door supporting position.

90 6. In a dump car, a discharge door, members movable into and out of supporting positions with said door, inter-engaging links connected with said members movable relative to each other in the direction of their lengths, and means carried by one of said links adapted to engage the other of said links to lock said members in their door supporting positions.

95 7. In a dump car, a discharge door, members movable into and out of supporting positions with said door, links connected with said members and movable longitudinally therewith relative to each other, and a locking member common to both of said links 100 for locking said members in their door supporting positions.

105 8. In a dump car, a discharge door, members movable into and out of supporting positions with said door, and means for locking said members in their door supporting 110

- positions, said means comprising a pair of links having their adjacent ends slidably connected together and their opposite ends pivotally connected with said links, and 5 means cooperating with said links to lock said members in their door supporting positions.
9. In a dump car, a discharge door, members movable into and out of supporting positions with said door, links connected with 10 said members and movable thereby in the direction of their length relative to each other and means adapted to cooperate with said links to lock said members in their door supporting positions.
- 15 10. In a dump car, a discharge door, door supporting and releasing members pivotally mounted on said car, means extending between and connected with said members for locking them in their door supporting positions, said means comprising a pair of links 20 movable in the direction of their length relative to each other by said members when said members are operated, and means cooperating with said links for locking said 25 members in their door supporting positions.
11. In a dump car, a discharge door, door
- supporting and releasing members pivotally mounted on said car, a link connected with each member and movable therewith, means whereby said links are movable relative to each other in the direction of their lengths when said members are operated, and means 30 adapted to cooperate with said links to lock said members in their door supporting positions.
12. In a dump car, a discharge door, door supporting and releasing members pivotally mounted on said car and locking means extending between and connected with said members, said means comprising a plurality 35 of slidably connected links whereby relative movement between said links is permitted when said members are operated, and means for preventing movement between said links when said members are in their door sup- 40 porting positions.
- 45

In testimony whereof I affix my signature in the presence of two witnesses.
